UNITED STATES PATENT OFFICE.

JAMES W. DE CAMP, OF BLACKWELL, OKLAHOMA, ASSIGNOR OF ONE-FOURTH TO CHARLES E. DE CAMP, OF BLACKWELL, OKLAHOMA, AND ONE-FOURTH TO JOHN P. MILLER, OF MUSKOGEE, OKLAHOMA.

CASKET-CARRYING HARNESS.

1,292,268.

Specification of Letters Patent. Patented Jan. 21, 1919.

Application filed June 15, 1917. Serial No. 174,989.

To all whom it may concern:

Be it known that I, JAMES W. DE CAMP, a citizen of the United States, residing at Blackwell, in the county of Kay and State of Oklahoma, have invented certain new and useful Improvements in Casket-Carrying Harness, of which the following is a specification.

This invention relates to harness for carrying and otherwise handling caskets and more particularly a glass casket of substantially the structure shown in my Patents Nos. 1,211,684, issued Jan. 9, 1917, 1,192,167, issued July 25, 1916, and 1,123,856, issued Jan. 5, 1915, reissued September 11, 1917, No. 14,357. The casket forming the subject-matter of the said patents has its body and lid constructed of glass and the said body and lid are bound by metallic frames formed of straps or bars, the two binding frames being connected by means of hinges at one side of the casket and the frame for the body of the casket being provided with handles. While such a casket is no more expensive than the ordinary wooden casket, nevertheless, it will, in practice, be found desirable to place upon the market a glass casket which will be less elaborate and which may therefore be sold at a lower price although all of the advantages to be derived from a glass casket are obtained. In order to reduce the cost of manufacture of such a casket under the stated conditions, it will be desirable to omit as many of the frame bars or straps as is possible without materially weakening the casket and also to dispense with the handles. At the same time it is necessary that means be provided whereby the casket may be conveniently carried and otherwise handled both before and during the funeral services. The present invention therefore aims to provide in connection with such a casket devoid of handles, a harness which may readily and quickly be applied to various sizes of the casket and which may be securely held assembled therewith although capable of being conveniently and quickly removed from the casket before the casket is lowered into the grave.

Another aim of the invention is to provide a harness for the purpose stated which will not in any way mar the finish of the casket when applied thereto or removed therefrom and which, when in position upon

the casket, will not interfere with free opening and closing of the lid of the casket.

In the accompanying drawings:

Figure 1 is a perspective view of the harness embodying the present invention applied to a casket substantially of the construction disclosed in my said patent;

Fig. 2 is a group perspective view illustrating parts of the handle and connecting bars of the harness;

Fig. 3 is a top plan view of the harness applied to the casket;

Fig. 4 is a vertical transverse sectional view on the line 4-4 of Fig. 3;

Fig. 5 is a vertical transverse sectional view on the line 5-5 of Fig. 3 with the casket removed;

Fig. 6 is a perspective view of one end of the harness removed from the casket;

Fig. 7 is a view similar to Fig. 5 but illustrating the harness applied to the casket and the said casket being shown in section.

The harness embodying the present invention is illustrated as applied to a casket including a body 1 and a lid 2, both molded from glass and the said body and lid have suitable, though not elaborate binding frames, there being a continuous frame bar 3 surrounding the upper side of the casket body and seating within a groove 4 formed in the outer faces of the sides and ends of the said body, a cushioning strip 5 of felt or the like being interposed between the said frame bar and the said faces of the walls of the casket body. Frame bars 6 are secured at their ends to the frame bar 3 and extend downwardly beside the side walls of the body 1 and beneath the bottom thereof, a wooden base 7 being disposed against the said bottom and retained in place by means of the said bars 6. In a like manner a continuous frame bar 8 extends about the lid 2 at the lower edges of the side and end walls thereof and other frame bars 9 are secured at their ends to the frame bar 8 and extend upwardly and transversely across the top of the said lid. Hinges 10 are secured to the frame bars 3 and 8 and serve to hingedly connect the lid with the body of the casket.

The harness embodying the present invention includes side handle bars and end connecting bars which extend between the side handle bars and serve to connect the same in

proper spaced relation. Each of the side handle bars comprises sections 11 and 12, the section 11 being telescopically fitted into the section 12 and the said section 12 being split 5 longitudinally at and adjacent its end which receives the section 11, as indicated by the numeral 13. A sleeve 14 is fitted on to the split end of the section 12 of each side handle bar and a set screw 15 is threaded 10 through the sleeve and when tightened bears against the split end of the section 12 and serves to frictionally bind the same about the end of the section 11. The sections 11 and 12 of each side handle bar are, of course, relatively 15 adjusted in accordance with the length of the casket with the harness to be applied. The ends of the two side handle bars are connected by means of end connecting bars, each comprising sections 16 and 17 telescopically 20 connected in the same manner as the sections 11 and 12 and each section 16 and 17 is provided in its outer end with an eye 18 receiving the reduced threaded end 19 of the section 11 or 12 of the respective side 25 handle bar, as the case may be. A hand grip 20 is provided with a threaded socket 21 and after the reduced ends 19 of the side handle bars have been fitted through the eyes 18 of the connecting bar sections, the hand grips 30 20 are threaded on to the said reduced ends 19 of the handle bars and all of the sections are thus connected in their proper relative 35 positions.

In order that the frame comprising the 35 side handle bars and connecting end bars may be supported against downward displacement a number of suspension devices are provided each including an attaching plate or member 22 relatively broad at its 40 upper end and formed at its said end with an overturned flange 23 which is preferably more or less thinned so as to permit of its being readily engaged over the upper edge of the frame bar 3. It will be understood 45 that the frame bars are held in slightly spaced relation to the outer faces of the walls of the body of the casket by means of the felt strips 5 and by reference to Fig. 7 it will be understood that the said flange 23 50 may bite or sink into the said cushioning strip 5 when the attaching members 22 are engaged with the frame bar 3. Short straps 24 are connected with the lower ends of the attaching member 22 and are passed beneath 55 and about the side handle bars and tightened by means of suitable buckles 25. Suspension straps 26 of webbing or any other similar material are passed beneath the bottom of the casket body and upwardly beside the 60 walls thereof and are looped about the side handle bars and tightened by means of buckles 27. It will now be understood that after the attaching members 22 have been disposed in place to properly support the 65 side handle bars, the straps 26 may be tight-

ened in the buckles 27 so as to exert a downward pull against the side handle bars so as to cause the harness to bind firmly to the said casket body. In order that the side handle bars of the harness may be held in 70 spaced relation to the outer faces of the side walls of the casket body, spacing blocks 28 are mounted upon the sections of the said side handle bars and bear against the outer faces of the side walls of the casket body, 75 the portions of the blocks which are presented toward the said walls being provided with flat bearing faces lined, as at 29, with felt or other suitable cushioning material. By providing the spacing blocks 28, the 80 buckles 25 and 27 may be readily manipulated and the straps 24 and 26 may be readily tightened, which, however, would be impractical if the side handle bars were held close to the outer faces of the side walls of 85 the casket body.

From the foregoing description of the invention it will be understood that the harness embodying the same may be readily applied to and removed from a casket 90 of the general type illustrated in the drawings and that therefore a casket devoid of handles and in other respects less elaborate and expensive than a casket designed in accordance with the illustration contained in 95 my said patents, may be employed.

Having thus described the invention, what is claimed as new is:

1. The combination with a casket having a band extending along its opposite sides, 100 of a harness for the casket including handle bars adjustable as to length, end bars connecting the handle bars and also adjustable as to length, means carried by the handle bars for detachable engagement with the 105 bands on the casket body, and suspension elements connected to and extending between the handle bars and adjustable longitudinally to accommodate the width of the end bars. 110

2. The combination with a casket having a band extending along its opposite sides, of a harness for the casket including handle bars, hook members detachably engageable with the band upon the casket, adjustable 115 connection between the hook members and the handle bars of the harness, and suspension elements extending between the said handle bars of the harness. 120

3. The combination with a casket having a band extending along its opposite sides, of a harness for the casket including handle bars, spacing members fitted upon said handle bars and having flat bearing faces adapted to engage the sides of the casket, 125 attaching members carried by the bars for engagement with the band of the casket and suspension members extending between the bars. 130

4. In casket harness, handle bars com-

- prising adjustably connected sections, longitudinally, adjustable end bars connecting the handle bars, spacing members carried by the handle bars and having flat bearing faces for engagement with the sides of the casket to which the harness is applied, attaching hooks, adjustable connections between the attaching hooks and the handle bars and suspension members extending between said handle bars.
5. The combination with a casket having a binding strap extending around its sides and ends, of harness for the casket including handle bars, hooks connected with the bars and detachably engageable with the upper edge of the band whereby to support the bars, and suspension elements extending between the bars.
10. The combination with a casket having a band extending along its opposite sides, of a harness for the casket including handle bars having reduced ends, connecting bars having eyes at their ends receiving the reduced ends of the handle bars, hand grips threaded on the reduced ends of the handle
- 15 bars and engaging the ends of the connecting bars, members carried by the handle bars and having means for detachable engagement with the band on the casket and suspension elements extending between said handle bars.
- 20 7. The combination with a casket having a band extending along its opposite sides, of a harness for the casket including handle bars, members carried by the handle bars and provided with means for detachable engagement with the band on the casket, and suspension elements extending between the handle bars of the harness.
- 25 8. A harness for carrying caskets of the type provided with a circumscribing band, comprising handle bars, members carried by the handle bars and provided with means for detachable engagement with the circumscribing band on the casket, and suspension elements connecting the handle bars and adapted to extend beneath the bottom of the casket.
- 30 40
- 45 In testimony whereof I affix my signature.
JAMES W. DE CAMP. [L.S.]
